VACUUM CLEANING CABINET FOR
DUST MOPSAlbert Deans Fairgrieve, Vancouver, British
Columbia, Canada

Application January 3, 1946, Serial No. 638,760

2 Claims. (Cl. 15—310)

1

My invention relates to improvements in vacuum cleaning cabinets which are particularly adapted for removing dust and flocculent material from dry mops.

The objects of the invention are to provide a cabinet in which a mop may be quickly and conveniently placed, and the dust etc. which adheres to it may be drawn out of it and deposited in a bag for subsequent removal; to provide that said mop may be properly agitated and that a current of air may pass through the mop from above and towards the free end of its strings. A further object is to provide for the air flow through and about the mop to be generally downwards, and a still further object is to provide a dust bag which is of ample size and capable of easy removal and cleaning.

The invention contemplates a cabinet having a bellows adapted to receive a mop head, whereby a current of air is developed within the cabinet and the mop is reciprocated in said air current, as will be more fully described in the following specification and shown in the accompanying drawings, in which:

Fig. 1 is a transverse sectional view of the invention.

Fig. 2 is a longitudinal view.

Fig. 3 is an enlarged fragmentary view of a portion of Fig. 1.

Fig. 4 is a detail view showing one of the bellows springs.

In the drawings like characters of reference indicate corresponding parts in each figure.

The numeral 1 indicates generally a cabinet having side walls 2, rear and front walls 3 and 4 respectively, a bottom wall 5 and a hingedly mounted door 6. Intermediate the height of the cabinet and extending around three of its sides is a rail 8 and at its upper edge a rail 9 is provided. Upon the rail 9 a bellows 10 is mounted having at its upper edge a frame 11 to which a cover 13 is hingedly connected. At a midposition along the front of the frame 11 an opening 14 is formed to receive the handle 15 of a mop 16, shown in dotted lines.

Supported from the rail 9 is a dust chute or cone 18 which narrows down towards its lower end to direct the dust from the mop 16 through a frame 20 into a fabric bag or receptacle 21 which is secured along its upper marginal edges to the frame 20 and is slidably carried upon the rail 8. The frame 20 is fitted on its underside with sponge rubber or other highly resilient packing 22 and is fitted with a vertical packing strip 23 on its forward edge as shown in Figure 2, to

engage the door 6 when in closed position and prevent any dust from escaping between said frame and the door. The frame 11 supporting the cover 13 is in turn supported on opposed vertical rods 25 which extend downwardly through collars 26 secured to the side walls of the cabinet 1. The rods are each fitted with a spring 28 which abuts a stop 29 on the rod and bears upon the collar 26 in which it moves, so that the bellows 10 may be held in resiliently extended position until manually depressed. The collars 26 are relatively large to allow the rods 25 to run very freely within them and the upper ends of said rods are preferably pivotally connected to the frame 11 as at 30.

The hinged cover 13 is fitted with a handle 31 by which said cover may be vertically reciprocated within the range of the bellows. The cover 13 is provided with a relatively large circular opening 31' having a bridge member 32 to which a spring loaded flap valve 33 is carried to cover the opening 31 and form an automatic inlet valve 34 for the upper portion of the cabinet. A bottom wall 35 is fitted at the base of the cone 18 and a spring loaded valve 36 is mounted in said wall in a similar manner to the mounting of the inlet valve 34 in the cover 11. The valve 36 serves as an outlet valve to pass dust from the mop held within the bellows down into the bag 21 and to prevent a return flow of the dust laden air. A bumper 38 consisting of a rubber coated horizontal bar 39 is supported above the rail 9 as shown in Figures 1 and 2, which is adapted to be engaged by the mop as it reaches the lower limit of its travel.

In operation, the cover 13 is raised, a mop 16 is placed therein and the cover closed down upon the mop handle 15 as shown in Figure 1. With one hand holding the handle 31 and the other hand holding the mop handle 15, the cover 13 and the bellows 10 and the mop 16 are reciprocated. If the operating stroke is long enough the mop handle will strike the bumper 38 to jar any adherent dust from the fabric of the mop. On the down stroke of the cover and associated parts, the inlet valve 34 remains closed, and the outlet valve 36 is opened, thus the air being driven in a downward stream by the collapsing of the bellows will carry the dust into the bag 21 and the air will pass through the fabric of said bag and pass out through the screen panel 40 provided in the lower part of the door 6. As the downward thrust on the cover 13 is relieved, the springs 28 will urge the bellows to distend to normal position as shown and as the cover re-

turns on its upward stroke the inlet valve 34 opens to admit air to the cabinet. The air flow being in a downward direction at all times ensures rapid removal of dust from the mop and its precipitation into the bag 21. At suitable intervals, the bag and its frame 20 are withdrawn from the rail 8 and the bag emptied of its dust content.

What I claim as my invention is:

1. A device for cleaning dry mops and the like comprising a cabinet having side walls, a bellows, a top wall connected to said side walls by said bellows, an air pervious dust receiver in the base of the cabinet and in communication with said bellows, a self-closing inlet valve in the top wall to admit air to the bellows and a self-closing outlet valve below the bellows and above the dust receiver to direct the air received from the bellows through the dust receiver, means for supporting a mop head within the bellows below the inlet valve, and means for distending the bellows, said cabinet having a wall opening to permit air passing through the dust receiver to pass outwards from the cabinet.

2. A device for cleaning mops and the like comprising side walls, a bellows carried by said side walls, said bellows having a top cover and a base opening, an air pervious dust receiver fitted into

5 said base opening, means for receiving and supporting a mop adjacent the cover whereby said mop will receive reciprocatory movement with a part of the bellows, a self-closing valve adapted to admit air adjacent the top of the bellows and a self-closing valve at the bottom of the bellows to direct air from the bellows through the dust receiver, a bumper mounted in the lower part of the bellows adapted to be struck by the mop as the bellows is reciprocated in one direction, and means for reciprocating the bellows.

ALBERT DEANS FAIRGRIEVE.
